DESIGN FOR A COMBINATION WEINER ROASTING APPARATUS AND DISPLAY HOUSING

Lloyd J. Bohannon, Kansas City, Mo.

Application November 25, 1935, Serial No. 59,755

Term of patent 14 years

To all whom it may concern:

Be it known that I, Lloyd J. Bohannon, a citizen of the United States of America, residing at Kansas City, Jackson County, Missouri, have invented a new, original, and ornamental Design for a Combination Weiner Roasting Apparatus and Display Housing, of which the following is a specification, reference being had to the accompanying drawing, forming a part thereof

In the drawing, the figure is a front perspective view of a combination weiner roasting apparatus and display housing, showing my new design, the opposite side being substantially plain.

I claim:—

The ornamental design for a combination weiner roasting apparatus and display housing, as shown and described.

LLOYD J. BOHANNON.
